UNITED STATES PATENT OFFICE

2,253,712

FASTENER

Emil Kern, Long Island City, N. Y., assignor to
Acco Products, Inc., Long Island City, N. Y., a
corporation of New York

Application August 19, 1939, Serial No. 290,982

4 Claims. (Cl. 24—153)

The invention relates to improvements in fasteners for binding papers, such as letters, in a file; and more particularly to an improved paper fastener, including a base having spaced prongs adapted to extend through holes in the papers and a novel compressor having similarly spaced apertures adapted to receive said prongs. The free ends of the prongs are adapted to be bent down over said compressor and held in place concealed by a cover.

An object of the invention is to provide the compressor of the foregoing type with efficient means for covering the prongs.

Another object is to provide a cover for a compressor of the type described that eliminates the excessive thickness objectionable in known types.

Another object is to provide a compressor, of the type having a slidable cover, pivotally mounted, with efficient means to frictionally hold said cover closed.

Another object is to provide a compressor with a cover embodying efficient structural details adapting it for inexpensive manufacture and simple and positive operation.

The foregoing and such other objects of the invention will be more readily understood from a perusal of the following specification in which reference is made to the accompanying drawing, wherein:

Fig. 1 is a plan view of one form of fastener.

Fig. 2 is a longitudinal sectional view of the fastener shown in Fig. 1.

Fig. 3 is a transverse sectional view taken on line 3—3 of Fig. 2.

Fig. 4 is a plan view of a fastener, showing one of its two covers in open position.

Fig. 5 is a longitudinal sectional view of another form of fastener, showing one of its covers in open position in dotted lines.

Fig. 6 is a fragmentary plan view of the fastener of Fig. 5.

In all figures, like numerals identify corresponding parts.

The fasteners illustrated are simple, inexpensive to manufacture and easy to operate. Each embodiment disclosed includes a base member 11 formed with spaced bendable prongs 12 adapted to be extended through openings in a stack of papers 13. The free ends of the prongs extend beyond the top of the stack through similarly spaced apertures 14 in a compressor 15 and are disposed over the compressor.

Referring specifically to the structure illustrated in Figs. 1 to 3 inclusive; the compressor 55

15 preferably is formed with longitudinal ribs 16 on its upper face, one spaced inwardly from each edge to define a central longitudinal channel 17 to receive the bent down ends of the prongs 12. An elevated strap 18 is struck up from the compressor adjacent one end. As shown, said strap spans the channel 17 and preferably is disposed at substantially the same elevation as the top of ribs 16.

10 A cover 19 is arranged on the compressor for movement over the bent down prongs to hold them over the top face of the compressor so as to insure tight binding of the papers. The cover 19 preferably includes an elongated strip of substantially stiff material adapted to be arranged so that one end lies beneath the strap 18 where it is held while in closed position, in the channel 17 over the bent down ends of the prongs. The other end of the cover 19 is pivotally and slidably secured to the compressor 15. As illustrated, the cover is longitudinally slotted, as at 24, and co-acts with a rivet 25 on the compressor. Hence the cover is slidable longitudinally a sufficient distance to disengage or engage its free end beneath the elevated strap 18.

20 An aperture 26 preferably is provided adjacent the free end of the cover to frictionally engage over a projection 27 on the bottom face of the strap to retard its longitudinal movement. Upon sliding the cover longitudinally to disengage its free end from beneath the strap, the cover may be rotated about rivet 25, as shown in dotted lines in Fig. 1, whereupon access may be had to the bent down prongs 12.

25 Fig. 4 illustrates a compressor having two covers 19a pivotally and slidably mounted one at each end of the compressor. The covers are locked in closed position, concealing the prongs 12, while their free ends are engaged beneath opposed lips 28. The lips 28 are struck upwardly from the compressor substantially midway between its ends. Each cover preferably is provided with a finger engaging apertured projection 29 adjacent its free end provided to facilitate 40 its sliding.

30 In the device shown in Figs. 5 and 6, the longitudinal margins 31 of the compressor are folded upwardly and inwardly. The closed ends 32 and the depressions 33 of said margins define transversely aligned short guides 34 to receive the T-shaped ends of the covers 19b. The inwardly turned margins 31 are wider at the medial portion of the compressor, to provide opposed elevated lips 28. As best shown in Fig. 5, to lock 35 the fastener, the covers are swung downwardly

against the prongs and then slid longitudinally to position their free ends beneath the lips 28 whereby said prongs are held in locked position. Projections 29 may be provided on each cover to facilitate finger engagement therewith.

Although exemplary forms of the improved covered prong fastener have been shown and described in detail, it is to be understood that, the disclosures are illustrative and not restrictive and may embody variations in detail structure without departing from the spirit of the invention of the scope of the appended claims.

I claim:

1. In a fastener for binding papers, the combination of, an elongated compressor plate 15 adapted to have prongs folded thereover, said plate having a longitudinal channel in its top face into which said prongs are folded, a transverse strap bridging said channel adjacent its other end of said plate, a cover hingedly and slidably connected at one end to said plate longitudinally slidable in said channel over said prongs and having its other end engageable beneath said strap when said cover is slid in one direction, and means on said cover and in said strap arranged to co-act to resist longitudinal sliding of the cover when engaged beneath said strap.

2. In a fastener for binding papers, the combination of, an elongated compressor plate 30 adapted to have prongs folded thereover, said plate having a longitudinal channel in its top face into which said prongs are folded, a transverse strap bridging said channel adjacent one end of said plate, a cover longitudinally slidable 35 in said channel over said prongs having one end engageable beneath said strap when said cover is slid in one direction, and a pivotal connection joining the other end of said cover to said plate

whereby said cover is rotatable in a plane parallel to said plate when its free end is disengaged from beneath said strap, said connection embodying means to permit limited sliding of said cover.

3. In a fastener for binding papers, the combination of, an elongated compressor plate adapted to have prongs folded thereover, said plate having a longitudinal channel in its top face into which said prongs are folded, a transverse strap bridging said channel adjacent one end of said plate, a cover longitudinally slidable in said channel over said prongs, said cover having a hinged and slidable connection at one end with said plate and having its other end engageable beneath said strap when said cover is slid in one direction, and a detent projection in the bottom face of said strap arranged to frictionally engage in an aperture in said cover to resist movement of the cover from beneath said strap.

4. In a fastener for binding papers, the combination of, an elongated compressor plate adapted to have prongs folded thereover, said plate having a longitudinal channel in its top face into which said prongs are folded, a transverse strap bridging said channel adjacent one end of said plate, a cover longitudinally slidable in said channel over said prongs having one end engageable beneath said strap when said cover is slid in one direction, a longitudinal slot at the other end of said cover, and a pin on said cover cooperating with said slot to provide a slidable-hinge connection whereby said cover is rotatable in a plane parallel to said plate when its free end is disengaged by sliding it from beneath said strap.

EMIL KERN.
